[57] CLAIM

The ornamental design for a cap pouch, as shown and described.

DESCRIPTION

FIG. 1 is a front elevational view of the cap pouch of the present invention;

FIG. 2 is a rear elevational view of the cap pouch of FIG. 1;

FIG. 3 is a right side elevational view of the cap pouch of FIG. 1, the left view being a mirror image thereof;

FIG. 4 is a top plan view of the cap pouch of FIG. 1;

FIG. 5 is a bottom plan view of the cap pouch of FIG. 1; and,

FIG. 6 is a top, front, right side perspective view of the cap pouch of FIG. 1.

The broken lines showing of a cap in FIG. 5 is for illustrative purposes only and form no part of the claimed design as are the broken letters in FIGS. 1 and 6.
